UNITED STATES PATENT OFFICE.

BESSE OLDEN MASON, OF EAST ORANGE, NEW JERSEY, ASSIGNOR TO JAMES McCREEERY & COMPANY, OF NEW YORK, N. Y., A CORPORATION OF NEW YORK.

DESIGN FOR A HAT.

Application filed April 1, 1925. Serial No. 12,976. Term of patent 3½ years.

To all whom it may concern:

Be it known that I, BESSE OLDEN MASON, showing my design, and a citizen of the United States, residing at East Orange, in the county of Essex and State of New Jersey, have invented a new, original, and ornamental Design for a Hat, of which the following is a specification, shown.

reference being had to the accompanying drawing, forming a part thereof.

I claim:

The ornamental design for a hat, as shown.

BESSE OLDEN MASON.
